US0D1100100S

(12) **United States Design Patent** (10) **Patent No.:** **US D1,100,100 S**
(45) **Date of Patent:** **** Oct. 28, 2025**

(54) **PLAYGROUND ACCESSORY**

(71) Applicant: **Kompan A/S**, Odense SO (DK)

(72) Inventors: **Nikolaj Maj Bentsen**, Vejle O (DK);
Cathrine Luettge, Odense SO (DK)

(73) Assignee: **Kompan A/S**, Odense SO (DK)

(**) Term: **15 Years**

(21) Appl. No.: **29/828,858**

(22) Filed: **Mar. 1, 2022**

Related U.S. Application Data

(62) Division of application No. 35/510,823, filed on Aug. 14, 2020 (U.S. filing date under 35 U.S.C. 384), and having an international filing date of Aug. 14, 2020, now Pat. No. Des. 948,652.
